DESIGN FOR A TABLE COVER OR SIMILAR ARTICLE OF MANUFACTURE

Ludwig G. Rohner, Forest Hills, N. Y.

Application January 12, 1946, Serial No. 125,520

Term of patent 3½ years

(Cl. D92—26)

To all whom it may concern:

Be it known that I, Ludwig G. Rohner, a citizen of the United States, resident of Forest Hills, county of Queens, and State of New York, have invented a new, original, and ornamental Design for Table Cover or Similar Article of Manufacture, of which the following is a specification, reference being had to the accompanying drawing, forming part thereof.

The figure is a plan view of one quarter of a table cover, showing my new design, the other quarters being the same, but arranged in proper relation to complete the table cover.

I claim:

The ornamental design for a table cover or similar article of manufacture, as shown and described.

LUDWIG G. ROHNER.
